Cincinnatus Boyd

UNITED STATES PATENT OFFICE.

CINCINNATUS BOYD, OF LA PORTE, INDIANA.

SIDING GAGE AND BRACKET.

SPECIFICATION forming part of Letters Patent No. 243,357, dated June 28, 1881.

Application filed May 3, 1881. (No model.)

To all whom it may concern:

Be it known that I, CINCINNATUS BOYD, of La Porte, county of La Porte, and State of Indiana, have invented certain new and useful 5 Improvements in Siding Gages and Brackets, of which the following is a specification.

The invention consists in a siding gage and bracket made of one continuous piece of metal bent into the required form, as hereinafter set 10 forth.

In order to enable others skilled in the art to which my invention appertains to make and use the same, I will now proceed to describe its construction and operation, referring to the 15 annexed drawing, which forms a part of this specification.

The figure on the drawing represents a side view of my invention.

A represents the gage-bar, made of a rod of 20 metal or a continuous piece of wire bent rearward, as at A', and then forward, to form a bracket, B, the end of which is sharpened to form a barb to facilitate driving it into the wood.

C is a slide working upon the bar A, and 25 fastened at any point desired by a set-screw, a. The bar A may be graduated so as to adjust the slide C thereon for any desired width of siding.

Upon the bracket there slides an adjustable 30 and removable support, D, which may be rigid or elastic, for supporting the siding upon the bracket. The support is made adjustable upon the bracket for the purpose of accommodating 35 various thicknesses of siding, and removable for the reason that in putting up short pieces of siding the support is rather an obstacle in the way of the workman than a useful attachment. In working long pieces of siding the support 40 performs an important function—namely, that of holding the siding in place laterally, while the bracket supports it. The support is

secured in any desired position upon the bracket by means of a set-screw, b.

In applying this invention the slide C is 45 set upon the bar A at a distance from the bracket B equal to the width of the siding desired to be put on, minus the lap. The slide is then placed against the lower edge of the siding already in place, and the barb of the bracket 50 driven into the siding to support the piece to be put in place. The siding is then placed upon the bracket, and the support adjusted to hold it in place laterally, after which the support will be in position to hold the remaining 55 boards of the same thickness without further adjustment.

In putting up short pieces the support can be removed by loosening the set-screw, when it will be out of the way of the workman. 60

To remove the device a single tap from a hammer or other instrument will loosen it sufficiently to enable the person using it to withdraw the same.

Having described my invention, what I claim 65 as new, and desire to secure by Letters Patent, is—

1. As a new article of manufacture, a siding gage and bracket made of a continuous piece of wire bent into form, as shown, and provided with an adjusting-slide, and a supporting-spring adapted to slide upon the bracket and secured thereto, in the manner described. 70

2. A siding gage and bracket made of one continuous piece of wire bent into form as 75 shown, having a barb formed integral with the bracket, and provided with an adjusting-slide.

In testimony whereof I have signed my name to this specification in the presence of two subscribing witnesses.

CINCINNATUS BOYD.
